Inventors,
George W. Brown,
John E. Wilson:

By their Attorneys,

C. Brown & Co.

UNITED STATES PATENT OFFICE.

GEORGE WILLIAM BROWN AND JOHN E. WILSON, OF DURYEA, PA.

CAR-COUPING.

SPECIFICATION forming part of Letters Patent No. 338,135, dated March 16, 1886.

Application filed January 7, 1886. Serial No. 187,889. (No model.)

To all whom it may concern:

Be it known that we, GEORGE WILLIAM BROWN and JOHN E. WILSON, citizens of the United States, residing at Duryea, in the 5 county of Luzerne and State of Pennsylvania, have invented a new and useful Improvement in Draw-Bars and Couplings, of which the following is a specification, reference being had to the accompanying drawings.

10 Our invention relates to improvements in draw-bars and couplings for cars used in coal-mines and the like; and the novelty consists of the peculiar construction and combination of parts substantially as hereinafter fully set 15 forth, and specifically pointed out in the claims.

The object of our invention is to provide an improved device of the class named which is especially adapted for use upon cars that are employed to convey coal in or about a coal- 20 mine or the like, which device can be operated very quickly and easily without requiring the attendant to pass between the cars, so that the car can be readily disconnected from the winding-drum and rope of an engine when it reaches 25 the end of an incline without danger to the attendant; and a further object of our invention is to provide our device with improved means whereby the strain on the pivots will be reduced to a minimum; and the device is 30 simple, strong, and durable in construction, and comparatively cheap and inexpensive of manufacture.

Referring to the drawings, Figure 1 is a view showing our improved draft-bar and hook 35 connected to the rope of a winding-drum and a car. Fig. 2 is a detail perspective view of the draft-bar and hook detached. Fig. 3 is a longitudinal vertical sectional view through Fig. 2 on the line $x-x$ thereof, showing the position of the parts in dotted lines after disengagement with the car.

Like letters of reference indicate corresponding parts in all the figures of the drawings, referring to which—

45 A designates our improved draw-bar and hook. B designates the drawing-rope of a winding-drum, which is actuated by an engine, and C a car for conveying coal from a mine to a place of deposit.

50 The draw-bar A has a projecting lug or

shoulder, a, at one end, and to this lug a is connected a draft-eye, D, by means of a pivot pin or bolt, b, that passes through the lug a and enlarged ends or heads b' of the draft-eye, the lugs b' fitting on opposite sides of the lug 55 a and have the pivot-pin b secured therein. The rope, chain, cable, or other flexible connection, B, of the winding-drum is connected to the pivoted eye D, and the opposite end of the draw-bar A is connected to the car C by a 60 link, E, and a pivot pin or bolt or other suitable connection.

The draw-bar A has two upwardly-projecting lugs, f, at end thereof that is adjacent the car C, and which, for the sake of convenience, 65 we will term the "rear" end; and the draw-bar is further provided with a transverse groove or recess, f', in its upper face, and at a short distance in front of the lugs f.

G designates a clasp or hook, which has a 70 curved centrally-located tongue, g, at one end, which is arranged between and pivoted to the lugs f of the draw-bar, the rear end of the clasp being cut away on each side of its pivot-tongue g to bear on the inner faces of the lugs 75 f. This clasp G is adapted to be moved to a horizontal or vertical position on its pivot, and it is provided on its under face with a transverse groove, g', that is adapted to register with the groove f' of the draw-bar A when 80 the clasp lies in its horizontal position. The ends of the grooves f' g' are recessed, as shown, and when the grooves register they provide a socket for the reception and retention of one of the cross-bars of the link E. At its front 85 end the pivoted clasp has a lug or stud, h, provided with a transverse opening, h', and over this lug fits a locking device, I, which comprises a bow-shaped piece having its lower ends fitted on opposite side faces of the draw-bar and pivoted thereto, so as to move or oscillate back and forth to engage and release the lug of the pivoted clasp. The locking-bow I has a thumb-piece, i, for its convenient operation, and at one side it has a set-screw, i', 95 that is adapted to clamp the device rigidly in position.

A pin, J, is passed through the opening h' of the pivoted clasp, and this pin is secured by a chain, L', &c., to an eye of the pivoted 100

loop to prevent it from becoming detached and lost and to adapt the device for simultaneous operation.

The operation is as follows: The draft-eye 5 D is connected with the rope B of the winding-drum or a car ahead of the said draft-eye, and the link E of the succeeding car is secured in the grooves $f' g'$ by the pivoted loop I locking the clasp G in position, the pin J being 10 inserted in the recess or opening h' of the link-clasp G, and the cord L extended to a point outside of the car and suitably held in position. When the car C reaches the point where it is desired it shall remain or discharge its load, 15 the attendant or operator withdraws the pin J by pulling on the cord L, and the pin being connected to the pivoted loop I a continued pull on the cord draws the loop from engagement with the pivoted clasp. When the loop 20 is disengaged from the pivoted clasp, the continued strain or draft on the link E will serve to turn the pivoted clasp rearwardly, and thus allow the link to be freed. By means of the recesses in the clasp on opposite sides of the 25 pivot-lug g thereof, and which recesses bear on the upwardly-projecting lugs f , the strain exerted by the link E on the clasp and rear end of the draw-bar is taken up by said lugs f and away from the pivot pin or bolt between 30 the bar A and clasp G.

To connect a link, E, with the draw-bar and clasp, the pivoted clasp is thrown back and one of the cross-bars of the link fitted in the groove f' , after which the clasp is turned 35 down to secure the link between its groove and that of the draw-bar, the pivoted loop and transverse pin being adjusted as before described.

The thumb-screw is allowed to remain loose when the device is in use, but when it is detached from a car the said screw is tightened up to hold all the parts rigidly in place. 40

Having thus described our invention, what we claim as new is—

1. The combination of a recessed draw-bar, 45 a link-retaining clasp pivoted thereto at one end and having a recess that registers with the recess thereof, a locking-loop pivoted to the draw-bar and engaging the free end of the clasp, a transverse pin, J, passing through the 50 free end of the clasp and bearing against the loop, a rope, L, connected to the pin, and a rope, L', connected with the rope L and the pivoted loop, substantially as described.

2. The combination, in a draw-bar and coupling of the class described, of a bar, A, having a draft-eye, D, the transverse groove f' , and the lugs f , a clasp, G, having a lug, g , pivoted between and to the lugs f , and having a groove, g' , a loop, I, pivoted to the bar A and adapted 60 to confine the free end of the clasp G, a transverse pin, J, passing through the lug in front of the pivoted loop, a cord, L, connected to the pin, and a cord, L', connected to the cord L and the pivoted loop, substantially as de- 65 scribed.

In testimony that we claim the foregoing as our own we have hereto affixed our signatures in presence of two witnesses.

GEORGE WILLIAM BROWN.
JOHN E. WILSON.
